Their Attorney

UNITED STATES PATENT OFFICE.

ARTHUR D. AVERY AND BARTON MANBERT, OF LOS ANGELES, CALIFORNIA.

PHONOGRAPH-OPERATED GAME.

1,292,228.

Specification of Letters Patent.

Patented Jan. 21, 1919.

Application filed May 22, 1918. Serial No. 236,026.

To all whom it may concern:

Be it known that we, ARTHUR D. AVERY and BARTON MANBERT, both citizens of the United States, residing at Los Angeles, in 5 the county of Los Angeles and State of California, have jointly invented new and useful Improvements in Phonograph-Operated Games, of which the following is a specification.

10 This invention relates to phonograph-operated games, and has for its object to provide a new and novel game comprising, the combination with the rotating element or record table of a phonograph instrument, 15 of certain members and means which perform their functions coincident with or resultant in part upon, the rotation of such record-supporting member or rotating phonograph table. It will be understood that 20 the utilization of any other suitable rotating base or table, in substitution for the rotating record table of a phonograph, in this combination, will still be clearly within the spirit and domain of the invention, but 25 the game is particularly adapted to take advantage of the presence in so many homes of phonograph instruments with rotating record tables, which admirably coöperate with the other features of the game to provide 30 the working combination.

The invention has for further particular objects the provision of a new and useful and amusing and instructive and entertaining game of the general character stated, 35 which will be superior in point of relative simplicity and inexpensiveness of construction and organization, facility of adaptation to or association or combination with phonographic instruments or substitute mechanisms, which will be reliable and positive in operation, durable, convenient to manipulate and operate, and generally superior in attractiveness, utility, efficiency and serviceability.

40 With the above and other objects in view, the invention consists in the novel and useful provision, formation, combination, association and relative arrangement of parts, members and features, all as hereinafter described, shown in the drawing, and finally pointed out in claims.

In the drawing:

Figure 1 is a perspective view of a conventional phonographic instrument, or the 45 upper portion thereof, illustrating the combination of parts thereof with certain other

features and members to produce a resultant game combination embodying and exemplifying the invention;

Fig. 2 is a slightly enlarged detail face 60 plan view of a member of the game combination, in detached position;

Fig. 3 is a perspective view of a further member of the game combination, also in detached position, also on a slightly en- 65 larged scale; and

Fig. 4 is a similar view of a further or agitator member of the game combination shown in the other figures, and on a greatly enlarged scale, and indicating in dotted lines 70 various relative adjustments of the parts.

Corresponding parts in all the figures are designated by the same reference characters.

Referring with particularity to the drawing, the new game comprises the combination, with a rotating element or table A, as of a phonographic instrument B, having the usual swinging arm C, which carries the sound-reproducing elements D; of a member or disk E adapted to be positioned upon 75 such rotating element or table, concentric therewith, and to be rotated therewith; and an agitator F which coöperates with balls or other scoring devices e which are caused to move about upon the upper surface of 80 the disk E upon its rotation, responsive to 85 the action of the agitator F.

Preferably the disk E has a plurality of openings 5 adapted to receive the balls e, and so associated with pictorial matter or 90 reading matter or symbols or the like, as to produce a certain game reading when said balls find and come to rest in the respective openings. The disk is preferably provided with a retaining wall 6 which may comprise 95 a flexible strip of suitable material, and may be conveniently held to the periphery of the disk E by means of a plurality of slots or openings 7 which receive spaced peripheral projections 8 upon the disk, such disk 100 to that end being polygonal in its superficial plan. The ends of the flexible strip 6, after it has been applied to the periphery of the disk E may be held or drawn or secured together by a cord 9 fastened to one end 105 of the strip as at 10, and adapted to be looped about a button or the like 11 upon the other end of the strip.

The disk E has a central opening 12 which registers with the rotating axis of the table 110 A, and is adapted to receive freely one end of the agitator F, which latter may com-

prise two parts, *f* and *g*. The part *f* may be formed of a suitable length of stiff wire formed into a helix 13 at one end, to enter the central opening 12 in the disk, and 5 thence directed as at 14 in a straight arm developed into a downwardly projecting loop or finger 15 in turn terminating in an eye 16. The part *g* may likewise be formed of a length of stiff wire formed into an 10 elongated loop 17 providing a body portion adapted to register with the eye 16, and to be locked thereto in position of adjustment by a clamping device 18. From the loop 18 extends an upwardly arched hook 19 which 15 may be covered with rubber tubing or other soft material 20. When the centering helix 13 is inserted in the opening 12, the finger 15 will take its place just inside of the retaining wall 6, and the covered hook 19 20 may be thrown over the arm C, all as shown in Fig. 1. The parts *f* and *g* may be adjusted to extend the length of the agitator or may be adjusted relatively in an angular sense, all as shown in Fig. 4, and to adapt 25 the agitator to use with different forms and arrangements of phonograph arms.

The operation, method of use and advantages and features of attractiveness, amusement, education, and the like, incident to the 30 use of the new game, will be readily understood from the foregoing description, taken in connection with the accompanying drawing and the following statement:

With the parts in positions shown in Fig. 35 1, in which the disk E is partially broken away to expose the upper surface of the rotating table, the rotation of the table will cause the balls *e* to be violently thrown about in a general centrifugal action, within the 40 confines set by the retaining wall 6. When thrown against such wall they are in position to engage the agitator finger 15, which causes them to be again thrown about over the surface of the disk, until they finally 45 find and seat themselves in certain of the openings 5. When they are all thus located, the rotation of the table A is stopped, and the values or readings pertinent to the respective openings in which the balls rest, 50 are made note of in determining the results of the game or the winners, as the case may be.

It is manifest that many wide variations and changes and substitutions and adaptations may be made, all with respect to the 55 matter of the foregoing description and statement and drawing, in adapting the invention to varying conditions and kinds of use and service, in connection with the playing of various games, all without departing from the spirit of the invention.

Having thus disclosed our invention, we claim and desire to secure by Letters Patent:

1. A game of the character described including, in combination with a phonograph

formed with a rotary table, a separate disk supported removably upon the table and formed with a series of pockets, a retaining wall extending around the disk, objects loose upon the disk and adapted to be seated 70 within the pockets, and a fixed agitator arm extending over the disk for engagement with the before mentioned objects, said agitator arm being detachably applied to and supported by the phonograph. 75

2. A game of the character described including, in combination with a phonograph formed with a rotary table and reproducer carrying arm, of a disk supported on the table to rotate therewith and provided with 80 a series of pockets in the top thereof, a retaining wall extending around the disk, objects loose upon the disk and adapted to be seated in the pockets, and a fixed agitator arm extending over the disk, one end thereof being provided with means for engagement with the center of the disk while the other end thereof is provided with means for engagement with the reproducer carrying arm. 85

3. A game of the character described including, in combination with a phonograph formed with a rotary table and sound reproducing arm, a disk supported on the table and formed with a series of pockets, a retaining wall extending around the disk, objects loose upon the disk and adapted to be seated in the pockets, and a fixed agitator arm extending over the disk and formed in two adjustably connected sections which admit of the effective length of the arm being 100 increased or decreased, one end of the arm being provided with means for engaging the center of the disk, while the other end thereof is provided with means for engaging the reproducer carrying arm. 105

4. A game of the character described including, in combination with a phonograph formed with a rotary table and reproducer carrying arm, a disk supported on the table and provided with a series of pockets, a retaining wall extending around the disk, objects loose upon the disk and adapted to be seated within the pockets, a fixed agitator arm extending radially over the disk and formed in adjustably connected sections, one 110 end of the arm being provided with means for engaging the center of the disk, while the other end thereof is provided with means for engaging the sound reproducing arm, and an agitating finger extending 115 downwardly from the arm adjacent the retaining wall. 120

5. A game of the character described including, in combination with a phonograph formed with a rotary table and reproducer carrying arm, a disk supported upon the table and formed with a series of pockets and also with a central opening, a retaining wall extending around the disk, objects loose upon the disk and adapted to be seated with- 125 130

- in the pockets, a fixed agitator arm extending over the disk and provided at one end thereof with means for engaging the central opening of the disk and at the other end thereof with a hook for engaging the reproducer carrying arm.
6. A game of the character described including, in combination with a phonograph formed with a rotary table and reproducer carrying arm, a disk supported upon the table and formed with a series of pockets and also with a central opening, a retaining wall extending around the disk, objects loose upon the disk and adapted to be seated in the pockets, a fixed agitator arm extending over the disk and formed in adjustably connected sections, one end of the arm terminating in a downwardly extending coil adapted to engage the central opening of the disk while the other end thereof terminates in a hooked portion adapted to engage the reproducer carrying arm, and an agitator finger extending downwardly from the arm at a point adjacent the retaining wall.
7. A game of the character described including, in combination with a phonograph formed with a rotary table and reproducer carrying arm, a disk supported upon the

table and formed with a series of pockets, objects loose upon the disk and adapted to be seated in the pockets, and an agitator arm extending over the disk for engagement with the objects when the disk is rotated, said agitator arm extending between the center of the disk and the reproducer carrying arm.

8. In a game of the character disclosed, a rotating member, said rotating member being associated with the record-supporting table of a phonograph instrument, such phonograph instrument having a swinging arm provided with sound-reproducing means, and an agitator for objects adapted to traverse the surface of the rotating member, such agitator being adapted to be supported at one end at the center of said rotating element, and being formed to be engaged with said arm as a support for the other end of the agitator.

In testimony whereof, we have signed our names to this specification in the presence of two subscribing witnesses.

ARTHUR D. AVERY.
BARTON MANBERT.
